UNITED STATES PATENT OFFICE

2,687,662

ADJUSTING-SCREW LOCK FOR SLIDABLE JAW WRENCHES

Stanford W. Pugh, Independence, Kans.

Application December 20, 1951, Serial No. 262,545

3 Claims. (Cl. 81—165)

1

This invention relates to adjustable wrenches and has for its principal object providing a wrench having a releasable locking pin journaling and engaging the worm to hold the jaws positively in a desired adjusted position.

A further object is to provide an adjustable wrench in which the releasable locking device is disposed on one edge of the head of the wrench in order to avoid interference with the use of the wrench jaws and head in application to the work.

A still further object is to provide an apparatus of this character which will be simple and economical of construction, efficient in operation and which will not readily deteriorate or become out of order.

Other objects and advantages of my invention will become apparent during the course of the following description, in which:

Figure 1 is a fragmentary side elevation of the head of an adjustable wrench constructed in accordance with the invention showing the locking means in released position.

Figure 2 is a fragmentary top plan view of the wrench head shown in Figure 1.

Figure 3 is a fragmentary side elevation of the head of the wrench with portions broken away to show the locking means in locked position.

Figure 4 is a side elevation of the locking pin.

Figure 5 is a cross-sectional view of a modified worm gear showing the locking device in operative position.

Referring now to the drawing in which like characters of reference designate similar parts in the various views, the wrench includes a handle 10 having an integral head 11 provided with a fixed jaw 12. The fixed jaw cooperates with a movable jaw 13 having an integral rack 14.

Rack 14 is slidably mounted in a slot 15 formed in the wrench head 11. The head is likewise provided with a rectangular opening 16 to receive a worm 17 which engages the rack 14 and may be turned by the operator's fingers to move the movable jaw 13 toward or away from the fixed jaw 12. These parts are conventional.

For the purpose of locking the wrench, a locking pin 18 is provided and shown most clearly in Figure 4. The locking pin 18 is provided with a knurled head 19 at its outer end and a bolt thread 20 at its inner end. A shoulder 21 is cut into the body of the locking pin midway between its ends. The shoulder 21 is not cut at a right angle with respect to the longitudinal axis of the locking pin 18. Instead, the shoulder is cut at an angle differing from the right angle 50

position by about 10°, although the angle may vary substantially.

The head of the wrench is provided with a cylindrical bore 22 in which the body of the locking pin 18 rotates. The head 11 is also provided with an inwardly threaded bore 23 in which the inner end of the locking pin 18 may be threaded.

The longitudinal axes of both bores 22, 23 are aligned and the center of the worm 17 forms a bore 24 of the same diameter as pin 18.

In operation, the locking pin, disposed in bores 22, 23, and 24, is withdrawn along its threads 20 so that the shoulder 21 does not contact the end of worm 17. The worm is rotated on the shaft of the locking pin between shoulder 21 and threads 20, moving the rack 14 and its integral jaw 13 to the desired position.

The locking pin is then rotated so that shoulder 21 is pressed tightly against worm 17, as in Figure 3. Sufficient pressure is applied to the worm to lock the worm against rotation and to take up any play between movable jaw rack 14 and worm 17. In order to release the worm, it is merely necessary to reverse the rotation of the locking pin, removing the shoulder 21 from its bearing against the worm.

In Figure 5 is shown another form of my locking device in which the locking pin 25 is provided with a taper 26. The worm 27 is provided with a cooperative tapered bore 28. Rotating the head 29 of the locking pin sets the taper 26 firmly in the tapered bore 28, so that the worm cannot be turned against the pressure produced in the taper joint.

It is to be understood that other variations of the specific device herein shown and described for the purposes of illustration may be made without departing from the spirit of the invention and the exclusive use of those modifications coming within the scope of the claims is contemplated.

What is claimed is:

1. An adjustable wrench comprising a stationary jaw provided with a handle, a movable jaw slidably mounted on the stationary jaw, a locking pin journaled in said stationary jaw with its axis disposed in the direction of the sliding movement of the movable jaw, the pin having an inner end threaded into the stationary jaw and an outer end projecting therefrom for manual engagement, a manually operable worm journaled on said pin and having threaded engagement with the movable jaw to actuate the latter, said pin and worm having engageable surfaces opposing each other lengthwise of the pin

and worm axis and forced against each other when the pin is rotated in one direction to frictionally lock the worm against rotation.

2. An adjustable wrench according to claim 1 wherein one of said engageable surfaces forms a shoulder bearing carried by and inclined to the longitudinal axis of the pin and the other of said surfaces forms a shoulder bearing on an end of the worm.

3. An adjustable wrench according to claim 1 wherein one of said engageable surfaces comprises a tapered shoulder on said locking pin surrounding its axis and arranged to bear against the other surface.
